DIGITAL SWITCH UNIT

James M. Powell, Anaheim, Calif., assignor to Endevco Corporation, Pasadena, Calif., a corporation of California

Filed June 15, 1959, Ser. No. 56,358

Term of patent 14 years

(Cl. D26—13)

FIG. 1.

FIG. 2.

FIG. 3.

FIG. 4.

Figure 1 is a perspective view of a digital switch unit, showing my new design;

Figure 2 is a side elevational view, the opposite side being substantially a mirror image thereof;

Figure 3 is a front elevational view; and

Figure 4 is a fragmentary side elevational view from the side opposite that shown in Figure 2.

The dominant features of my new design are shown in solid lines in the drawing. A plurality of units as shown may be assembled in side by side relation.

I claim:

The ornamental design for a digital switch unit, as shown and described.
